UNITED STATES PATENT OFFICE

SAMUEL HAMMER, OF BROOKLYN, NEW YORK, ASSIGNOR, BY MESNE ASSIGNMENTS, TO ROACH-APPLETON MANUFACTURING COMPANY, OF CHICAGO, ILLINOIS, A CORPORATION OF ILLINOIS

KNOCK-OUT FOR ELECTRIC JUNCTION BOXES, SWITCH BOXES, ETC.

Original No. 1,721,593, dated July 23, 1929, Serial No. 155,163, filed December 16, 1926. Application for reissue filed March 20, 1930. Serial No. 437,615.

This invention relates to knock-outs for electric junction boxes, switch boxes, etc., and has for its primary object to provide one or more walls of the box structure with integrally connected sections or discs which may be readily detached or separated from the box wall to provide openings therethrough for the lead-in wires without necessitating the use of a hammer.

It is a more particular object of the invention to provide each of the knock-out discs or sections with an outwardly projecting part or lip with which the point of a screw-driver may be readily engaged and the necessary leverage applied to separate said disc at its perimeter from the box wall; thus the box structure is not subjected to a severe shock or vibration which might possibly result in injury or derangement of the parts of the mechanism associated therewith, which is not an infrequent occurrence when such junction boxes are used in connection with electrically controlled clocks or other comparatively delicate mechanisms.

It is a further general object of my present improvements to provide a knock-out for electrical junction or switch boxes as above characterized which involves no additional operations in the present method of manufacturing such boxes, and therefore entails no additional manufacturing cost.

With the above and other objects in view, the invention consists in the improved knock-out for junction or switch boxes and in the form and construction of the several features thereof as will be hereinafter more fully described, illustrated in the accompanying drawings and subsequently incorporated in the subjoined claims.

In the drawing, wherein I have disclosed one simple and practical embodiment of my present improvements and in which similar reference characters designate corresponding parts throughout the several views,—

Figure 1 is a front elevation of an electric switch box provided with my present improvement and showing the cover in open position;

Figure 2 is an enlarged elevation of one

of the box walls provided with my improved knock-outs;

Figure 3 is an edge view thereof, and

Figure 4 is a detail sectional view taken on the line 4—4 of Figure 2.

Referring in detail to the drawing, 5 generally designates the body of the junction or switch box, the several walls of which are in the form of sheet metal stampings. To the side walls of the box body 5 at one end thereof, the cover or closure for the open side of the box indicated at 6 is hingedly connected. Further detailed description of the box construction is unnecessary, as the invention constituting the subject matter of this application may be advantageously employed upon various types and constructions of such boxes now generally used in this art.

As herein shown, in the formation or stamping of the end or side walls of the box, 70 at properly located points circular disc-like sections 7 are subjected to pressure by parts of the stamping die and partially projected from the general plane of the box wall, as clearly shown in Figure 4 of the drawing. 75 However, these discs at their perimeters remain integrally connected with the wall structure by a comparatively thin fin of metal as indicated at 8. The line of rupture of the metal, it will be observed, lies along a single 80 line. This weakened connection between the discs and the box wall will permit the complete separation of the discs from said wall by the application of leverage or pulling effect to the edge of the disc. In order that such leverage or pulling effect may be readily applied, a minor part of the disc at its edge is completely separated from the box wall and angularly projected outwardly beyond the plane of said disc to form a lip 9. 85 The portion 8 constitutes an intact portion which is disrupted in the removal of the corresponding section 7. Said lip 9 is symmetrically disposed relative to said portion 8.

In the use of such electrical junction boxes in connection with electrical clocks or other mechanisms, the box is suitably mounted within the clock case, and in the installation of the clock the discs 7 are removed from that wall of the box so as to provide the openings

therethrough most conveniently located with respect to the arrangement of the wiring in the building, so that the lead-in wires may be passed through said openings. Heretofore, these knockout discs have been integral-
 5 ly connected throughout their circumferential edges with the box wall, and it has been necessary to remove said discs by striking the same several severe blows with a hammer.
 10 It has been found that in many cases this results through the jar or vibration, in de-
 15 rangement of the parts of the delicate clock mechanism, and as the space in which the hammer may be welded is comparatively re-
 20 stricted, there is also great liability of the hammer striking parts of the mechanism and seriously damaging the same so that they have to be replaced. It will be apparent that by means of my present improvements
 25 it is not necessary to subject the box struc-
 30 ture or the casing within which it is mounted to such severe vibrations, as the discs 7 can be readily removed by merely inserting the point of a screw-driver or other implement,
 35 as indicated at 10, beneath the lip 9 and prying outwardly while the point of the screw-
 40 driver is in bearing contact against the face of the box wall. Thus, the relatively thin fin 8 at the perimeter of the disc may be rup-
 45 tured and the disc completely separated from the box wall to provide the necessary open-
 50 ing therein. It will be apparent that this operation may be very quickly performed without the slightest jar or vibration of the
 55 box structure so that there is no possibility of injury to parts contained therein or to the mechanism which may be associated there-
 60 with.

From the foregoing description considered
 40 in connection with the accompanying draw-
 45 ing, the construction and manner of use of
 50 my improved knock-out construction for
 55 electric switch or junction boxes will be clear-
 60 ly understood. The device may of course be
 65 also advantageously employed in connection
 70 with various other forms of electrical appa-
 75 ratus housed within a box or casing. Like-
 80 wise, the particular shape and size of the
 85 disc 7 or the form and arrangement of the lip
 9 or other means with which the tool is
 90 adapted to be engaged is not material and
 95 may be variously modified as may be found
 100 desirable to satisfactorily meet different con-
 105 ditions. Therefore, while I have herein
 110 shown and described one simple and practi-
 115 cal embodiment of the device which has given
 120 excellent results in actual use, it is neverthe-
 125 less to be understood that the invention is sus-
 130 ceptible of embodiment in various other al-
 135 ternative forms, and I accordingly reserve
 140 the privilege of resorting to all such legiti-
 145 mate changes in the essential features thereof
 150 as may be fairly embodied within the spirit
 155 and scope of the invention as claimed.

65 What is claimed is—

1. A metal container for electrical appa-
 70 ratus having a wall with a removable portion
 75 marked out thereon, said portion being integral
 80 with said wall and connected therewith
 85 around the greater part of its periphery by
 90 a metal fin which is thin enough to permit
 95 the ready separation of said portion of said
 100 wall, said fin being too thin to permit bend-
 105 ing without breaking, the remaining portion
 110 of the periphery being bent to form a
 115 lateral projection to permit an implement to
 120 be inserted under said projection to break out
 125 said portion.

2. A metal structure having a wall with a
 80 removable portion marked out thereon, said
 85 portion being integral with said wall and
 90 connected therewith by an intact portion to
 95 permit the ready separation of said removable
 100 portion from said wall, the remaining
 105 portion of the periphery of said removable
 110 portion being formed to provide an abutment
 115 to permit an implement to be engaged there-
 120 with to break out said removable portion.

3. In a metal structure, in combination, a
 90 wall portion having a removable portion
 95 forming part thereof, said removable portion
 100 being defined by a single line of rupture
 105 interrupted by a single intact portion, the
 110 edge portion of said removable portion sym-
 115 metrical with said intact portion being
 120 formed with means for engagement with a
 125 tool for breaking out said knock-out.

4. A metal structure having a wall portion
 100 provided with a removable portion, said re-
 105 movable portion being defined by a single
 110 line of rupture, the edge portion of said re-
 115 movable portion being formed with an abut-
 120 ment for the reception of a tool for breaking
 125 out said knock-out.

5. A metal structure having a wall portion
 130 provided with a removable portion, said re-
 135 movable portion being defined by a single
 140 line of rupture, said removable portion being
 145 formed, symmetrically with said line of rup-
 150 ture, with abutment means for the reception
 155 of a tool for breaking out said knock-out.

6. A metal structure having a wall portion
 115 provided with a removable portion, said re-
 120 movable portion being defined by a single line
 125 of rupture, an edge portion of said remov-
 130 able portion symmetrical with reference to
 135 said line of rupture being formed with abut-
 140 ment means for the reception of a tool for
 145 breaking out said knock-out.

7. In a metal structure, in combination, a
 150 wall portion having a removable portion
 155 forming a part thereof, said removable portion
 160 being defined by a single line of rupture
 165 interrupted on one side only of said remov-
 170 able portion by a portion symmetrically dis-
 175 posed relative to said line of weakened ma-
 180 terial, said one side of said removable por-
 185 tion being formed with means for engage-

ment with a tool for breaking out said knock-out.

8. A metal structure having a wall portion provided with a removable portion, said removable portion being defined by a single line of rupture having the outline of a geometrical figure, said removable portion being formed on one side of said geometrical figure with an abutment for the reception of a tool for breaking out said knock-out.

10. Signed at Brooklyn, New York, the 10th day of March, 1930.

SAMUEL HAMMER.
